UNITED STATES PATENT OFFICE.

HARRIET REDDIN, OF ATTLEBORO, MASSACHUSETTS.

OVEN-SHELF.

1,216,164.

Specification of Letters Patent. Patented Feb. 13, 1917.

Application filed June 16, 1916. Serial No. 104,026.

To all whom it may concern:

Be it known that I, HARRIET REDDIN, a citizen of the United States, residing at Attleboro, in the county of Bristol and State of Massachusetts, have invented new and useful Improvements in Oven-Shelves, of which the following is a specification.

The invention relates to an improvement in ovens and particularly to a movable shelf, in the use of which the shelf may be caused to occupy a position wholly within the oven for baking purposes, or be withdrawn therefrom in order that the material on the shelf may be conveniently exposed, removed or changed as desired.

The invention comprehends a shelf movably supported on ledges preferably by roller supports with the forward edge of the shelf connected to the upper portion of the stove or oven proper by flexible connections whereby the shelf may be moved from the oven and supported in practically horizontal position.

The invention in the preferred form of details will be described in the following specification, reference being had particularly to the accompanying drawings, in which:—

Figure 1 is a perspective view of a portion of a stove illustrating the oven and the improved shelf;

Fig. 2 is a longitudinal section of Fig. 1.

Fig. 3 is a sectional view through the shelf illustrating additional supporting rollers.

The improved shelf 1 is, aside from the details hereinafter noted, of any usual or preferred construction, being arranged to fit within the oven 2, to support articles to be baked.

For the purposes of the present invention, I secure on each side wall 3 of the oven, supporting ledges 4, arranged in superimposed series, preferably metallic strips formed with a series of transverse grooves 5. The shelf 1 is provided adjacent each side edge with depending brackets 6 in which are mounted a number of rollers 7 adapted for travel on the ledges 4, the peripheral edges of the rollers being also formed with transverse grooves 8.

The forward edge of the shelf is provided with flexible connectors 9, preferably chains, and the stove body preferably within the openings is provided with hooks 10 with which any one of the links of the chains may be removably connected.

As the shelf is adapted for coöperation with either pair of ledges 4 and as the chains are designed for supporting the shelf when in coöperation with either pair of ledges, it is preferred that the chain be provided at determinate points with rings, as 10', any one of which, in accordance with the particular pair of ledges with which the shelf 65 is arranged to coöperate may be engaged with a hook 10. Furthermore the side walls of the oven immediately above the ledges 4 are provided with guide lugs 11 beneath which the shelf slides in operation, the lugs 70 serving to support the shelf in movement and against tilting. The forward portion of the shelf is preferably formed with an opening 12 to permit the insertion of a poker or other implement in withdrawing 75 the shelf while in heated condition.

The groove formation, or practical roughening of the ledges and rollers, prevents slipping of the parts and insures the wheels properly gripping the ledges in the full extended position of the shelf. The grooved rollers and rack, by insuring the shelf against slipping, enables the user to place the shelf at any length of projection with relation to the oven, and place a pan or 85 dish thereon by sliding the same in contact with the shelf, without danger of the shelf moving during the operation. Of course, I contemplate forming the shelf in any desired manner other than the specific details above noted, using any appropriate material and making it of any size and shape to coöperate with the desired oven.

The improvement permits articles to be baked in the usual manner, and the shelf 95 as an entirety moved forwardly to any desired position beyond the oven so that the articles supported on the shelf are wholly clear to permit inspection, removal, seasoning, or the like.

What is claimed is:

The combination with an oven, ledges se-

cured to the sides thereof, and having transversely grooved upper surfaces, of a shelf, rollers mounted on the underside thereof to engage the ledges, said rollers having transversely grooved peripheral surfaces, guide lugs projecting from the oven and overlying and bearing upon the shelf to prevent

tilting of the latter when projected beyond the oven, chains connected to the forward edge of the shelf, and hooks secured to a fixed part of the oven and adapted to removably receive different parts of the chain.

In testimony whereof I affix my signature.
HARRIET REDDIN.
